C. DE MOOS

FLUID TREATING APPARATUS FOR FILMS

Filed Feb. 3, 1922

FIG. 2.

WITNESS

FIG. 3.

INVENTOR

CHARLES DE MOOS,
BY R. L. STINCHFIELD

ATTORNEY

UNITED STATES PATENT OFFICE.

CHARLES DE MOOS, OF FORT LEE, NEW JERSEY, ASSIGNEE TO EASTMAN KODAK COMPANY, OF ROCHESTER, NEW YORK, A CORPORATION OF NEW YORK.

FLUID-TREATING APPARATUS FOR FILMS.

Application filed February 8, 1922. Serial No. 583,824.

To all whom it may concern:

Be it known that I, CHARLES DE MOOS, a citizen of the United States of America, residing at Fort Lee, in the county of Bergen and State of New Jersey, have invented certain new and useful Improvements in Fluid-Treating Apparatus for Films, of which the following is a full, clear, and exact specification.

10 This invention relates to apparatus in which strips of material, such as motion picture film, are subjected to the action of fluids like those for developing, washing, fixing, tinting, toning, drying, etc. One 15 object of the invention is to provide an apparatus in which the film, especially that of usual type having two sets of perforations therein, is conducted with certainty and without injury through the vessels in 20 which the treatment takes place. Other objects will hereinafter appear.

In the accompanying drawing:

Fig. 1 is a fragmentary vertical sectional view through a typical portion of a fluid 25 treating apparatus embodying the preferred form of my invention;

Fig. 2 is a plan view of the same;

Fig. 3 is a diagrammatic plan view of the sprocket arrangement used in the preferred form.

In all of the figures the relative dimensions of the parts are somewhat altered for the sake of clearness and compactness in illustration.

35 In commercial apparatus for fluid treating motion picture film it has been proposed to pass the film through one or more tanks or vessels in a series of loops by means of toothed sprockets engaging the perforations 40 adjacent the opposite edges of the film, each sprocket having two separate sets of teeth for this purpose. In actual practice trouble is experienced due to a slight distortion of the film during treatment. This results in 45 injury to the perforations. When the perforations at one edge of the film are properly engaged by one of the sets of teeth of the sprocket, the perforations at the other edge, due to the distortion, are slightly too 50 far ahead or slightly too far back of the position that they should occupy with respect to the other set of teeth. Consequently, the film rides up on these teeth. Since the film is under some tension, this riding portion 55 of the film between the perforations becomes

scratched. But the worst effect occurs when the teeth are finally forced into the perforations with which they do not perfectly register. This forcing mutilates the edges of the perforations, correspondingly impairing the usefulness of the finished product for projection. I have discovered that this serious difficulty can be overcome by providing a series of perforation-engaging tractive members; such that certain of them engage only one set of perforations in the film and others engage only the opposite set of perforations. In the preferred embodiment of my invention these tractive members take the form of sprockets, each having a single set of teeth, the teeth of successive sprockets throughout the series engaging opposite sets of perforations in the film.

The fluid treatment vessels are shown at 1 in the form of vertical tubes or tanks of circular cross section. Of course, these may be of quite different shape and in general are sufficiently long to provide for adequate treatment of the film while it moves therethrough. They are shown as containing liquid 2 which may be any of those used in the treatment of photographic film. For the customary developing and fixing baths tubes of lead have been found satisfactory. 35 In place of a liquid, a drying fluid, such as warm air, can be passed through the vessels to properly condition the film. Adjacent the top of the tanks is located a support 3 having bearings 4 in which rotate shafts 5 rotated in unison by any convenient means, such as chains 6, meshing with chain sprockets 7 deriving power from a drive shaft 8.

On each shaft 5 is a sprocket 9. So long as these have the particular arrangement of tractive members, mentioned later, they may be of any ordinary or preferred form. They are illustrated as having guide flanges 10 and cutaway central portions 11, leaving 100 film bearing ledges 12. These details, however, are not essential, although convenient.

As shown most clearly in Fig. 3, each sprocket has only one set of perforation-engaging teeth 13. The set of teeth on each sprocket is at the end opposite the set of teeth on the next adjacent sprocket. In other words, the teeth of the successive sprockets alternately engage the opposite sets of perforations 14 in film 15.

In order to maintain the film in looped condition in the fluid treating vessels or tanks and in contact with the sprockets, it is convenient to employ weighted rollers 16 having flanges 17 thereon and film engaging ledges 18 formed by cutting away the central portions of the rolls at 19.

It will be understood that I have shown only a part of the apparatus in which the 10 principle of my invention is illustratively embodied, as will be obvious from an inspection of the drawing. The shape of the fluid treating vessels can be widely varied and the number of them can be greatly changed or 15 increased. Moreover, the number of film-contacting sprockets used in connection with each tank or container can be varied in accordance with ordinary engineering practice.

20 I find that film which has been treated and moved by the method above described is not permanently distorted, but in its finished condition is eminently suitable for projection without trouble. Neither the temporary 25 distortion which takes place in the fluids, nor the stresses set up by engaging the film at opposite sides at separate points causes any permanent impairment.

Having thus described my invention, what 30 I claim as new and desire to secure by Letters Patent is:

1. Apparatus for fluid treating motion picture film having sets of perforations therein, comprising treatment vessels and 35 means for conducting said film through said vessels, said means including a series of perforation-engaging tractive members, certain of said members engaging only one set of perforations and others engaging only another set of perforations.

2. Apparatus for fluid treating motion picture film having sets of perforations therein, comprising treatment vessels and means for conducting said film through said 45 vessels, said means including a series of perforation-engaging tractive members, each member of said series engaging only a set of perforations different from the set engaged by the next member in the series.

50 3. Apparatus for fluid treating motion picture film having sets of perforations therein, fluid treatment tanks and means for conducting said film through said tanks, said means including a series of sprocket rolls, 55 the teeth of certain of said sprockets engaging only one set of perforations and the teeth of others engaging only another set of perforations.

4. Apparatus for fluid treating motion picture film having sets of perforations 60 therein, fluid treatment tanks and means for conducting said film through said tanks, said means including a series of sprocket rolls, each sprocket having a single set of teeth engaging only one set of perforations, the 65 teeth of successive sprockets in the series engaging different sets of perforations.

5. Apparatus for fluid treating motion picture film having two sets of perforations 70 therein, comprising fluid treatment tanks, sprockets driven in unison for conducting said film into and out of said tanks, and weighted rolls for maintaining film loops in 75 said tanks and holding said film in contact with said sprockets, each sprocket having only one set of teeth, and the teeth of each sprocket engaging a different set of perforations from those engaged by the teeth of the next sprocket.

6. Apparatus for fluid treating film having 80 two sets of perforations, comprising a fluid treatment chamber and sprockets for moving said film through said chamber, one of said sprockets having a single set of teeth engaging only one set of perforations and another of said sprockets having a single 85 set of teeth engaging only the other set of perforations.

7. A process of fluid treating film having 90 two sets of perforations, comprising the steps of bringing into contact with said film a fluid tending to distort it and applying moving forces while the film is so treated to said sets of perforations at longitudinally 95 separate zones, the zones of application of force to one set of perforations being staggered along the length of the film with respect to the zones of application of force to the other set of perforations.

8. Film advancing mechanism adapted to 100 effect the advancement of standard perforated motion picture film comprising a film driving roll having narrow film bearing ledges near the ends and sprocket teeth extending from one of said ledges only.

105 9. Film advancing mechanism adapted to effect the advancement of standard perforated motion picture film comprising a plurality of film driving rolls, each roll having narrow film bearing ledges near its ends and one of said ledges having sprocket teeth thereon, said rolls being arranged so that the toothed portions of successive rolls will engage the perforations on opposite sides of the film.

CHARLES DE MOOS.
